(Model.)

T. M. HART.

Cotton Scraper and Chopper.

No. 243,129.

Patented June 21, 1881.

N. PETERS. Photo-Lithographer. Washington, D. C.

UNITED STATES PATENT OFFICE.

THOMAS M. HART, OF WEBSTER, MISSOURI.

COTTON SCRAPER AND CHOPPER.

SPECIFICATION forming part of Letters Patent No. 243,129, dated June 21, 1881.

Application filed March 28, 1881. (Model.)

To all whom it may concern:

Be it known that I, THOMAS M. HART, a citizen of the United States, residing at Webster, in the county of Oregon, in the State of 5 Missouri, have invented a new and useful Improvement in Cotton Scrapers and Choppers, of which the following is a specification.

My invention relates to improvements in cotton scrapers and choppers in which adjustable revolving choppers are operated in conjunction with one or more adjustable scrapers which are so arranged as to precede the choppers; and the objects of my invention or improvements are, first, to provide scrapers which 10 may be raised or lowered, or be readily changed in their lateral position; second, to provide a revolving chopper which may be adjustable by lengthening or shortening the arms to which the choppers are attached; thirdly, to secure 15 strokes of the choppers at regular intervals and distances apart. I attain these objects by the mechanism illustrated in the accompanying drawings, in which—

Figure 1 is a perspective view, with part of 25 the shield over the chopper-arms broken away. Fig. 2 is a detailed longitudinal section. Fig. 3 is a transverse section. Fig. 4 is a top plan. Fig. 5 is a detailed view of chopper. Fig. 6 is a detailed plan of the cross-head.

Similar letters refer to similar parts throughout the several views.

In Fig. 1 the main frame A A is rectangular in form, with a tongue, A', extending in front and resting on axles O a', supported by wheels 35 B B' B'. The tongue A' is attached to the axle a' by a king-bolt, a, for draft and to facilitate turning the whole machine around. The wheels B' B' are rigidly held upon the axle O, which is secured to the frame A A by hanging-boxes attached, and on this axle is a beveled gear, D, secured in place by a set screw or pin, and intergearing with another beveled gear, D', rigidly attached to a revolving shaft, O², Fig. 2, which is supported at its geared 40 end by a box attached to a cross-beam of the frame A A, and at the opposite end by a similar box on the frame A A, in which boxes, by motion imparted to it through the axle O and the traction of the wheels B' B' upon the ground, 45 it is revolved at right angles to the axle O.

The two-armed cross-head C', Fig. 2, is recessed on its opposite face sides to receive and support the adjustable chopper-arms c c', and is held by a nutted bolt, C², extending through the slots c⁴ c⁴, cross-head C', and shaft O², as 55 shown in Fig. 6, so that the chopper-arms c c' may be shortened or lengthened.

C C', Fig. 2, is a longitudinal section, showing the slots c⁴ c⁴ at one end of the arm, and the curved and pronged part C, with the steel 60 choppers c² c³ attached at the opposite end, permitting the dirt to pass freely through.

Attached to the curved beams E E, Fig. 1, are the scrapers e e, of usual shape, and arranged one on each side of the tongue A', Fig. 65 3, and these beams are loosely fulcrumed thereto on the pin e', Fig. 1, so that they may be moved vertically or laterally, as i³ e i⁴ e.

The cross-bar H, Fig. 3, with a standard part, F, extending above and below it, is screw-threaded on both ends, and on each end has two or more nuts, h h', between which the 70 scraper-beams E E are held at any desired distance apart.

Upon the standard F', Fig. 3, is a spiral 75 spring, f, held by a nut, f², for adjusting the lever F, which is attached to the bottom by a pin, and is operated by the cross-bar G, Fig. 3, supported at one end by a standard-box and at the opposite end in the lower part of the 80 ratchet-gear G², Fig. 2, and is operated by the hand-lever G' and ratchet, whereby the scrapers may be raised or lowered.

i' i², Fig. 3, represent two foot-levers fulcrumed on the pin i³, and there crossing each 85 other, extending upward, so that the rider's feet may rest upon them for their operation, and extending below alongside the scrapers, as seen in Fig. 2, I I', for the purpose of moving them sidewise, as is indicated by the dotted lines i³ i⁴, Fig. 3.

I am aware of scrapers and revolving choppers being used for the purposes described, but each of them essentially differs from mine in its construction, parts, and combination. 95

Having thus fully described my invention, I claim as new and desire to secure by Letters Patent—

1. In a cotton scraper and chopper, the combination, with the frame A and tongue A', of 100

the curved scraper-beams E E, pivoted to the tongue at e' , the screw-threaded brace and spreader H, lifting-lever G', and geared chopper, with adjustable hose, as shown and described.

2. The pivoted beams E E, with adjusting-brace H, in combination with the rock-shaft G, arm F, pivoted standard F', spring f, lever G', and ratchet G², substantially as shown and described.

3. The pivoted beams E E, brace H, adjustable lever-arm F, and rock-shaft G, in combination with the foot-levers i' i^2 , having spring-extensions, and fulcrumed on a pin, i^3 , whereby the scraper-beams may be vibrated laterally, substantially as shown and described.

THOMAS M. HART.
